US00D385963S

United States Patent

[19]

Hansson[11] **Patent Number:** **Des. 385,963**[45] **Date of Patent:** ****Nov. 4, 1997**[54] **FEMURAL OSSEOIMPLANT**918531 9/1954 Germany .
1812973 4/1993 U.S.S.R. .... 606/71[75] **Inventor:** **Henrik Hansson**, Linköping, Sweden**OTHER PUBLICATIONS**[73] **Assignee:** **Collux AB**, Malmo, Sweden"Massie Sliding Nail", Zimmer, Warsaw IN. 1981, Catalog,
p. B170.[**] **Term:** **14 Years**[21] **Appl. No.:** **27,441****Primary Examiner**—Stella Reid
Attorney, Agent, or Firm—Ladas & Parry[22] **Filed:** **Aug. 22, 1994**[57] **CLAIM**[30] **Foreign Application Priority Data**The ornamental design for a femoral osseointerface, as shown
and described.

Feb. 21, 1994 [SE] Sweden 94-0425

[51] **LOC (6) Cl.** ..... **24-03****DESCRIPTION**[52] **U.S. Cl.** ..... **D24/155**FIG. 1 is a left side elevational view of a femoral osseointerface,
showing my new design, in assembled condition;[58] **Field of Search** D24/155; 623/23,
623/65, 67-69, 71, 73

FIG. 2 is a right side elevational view thereof;

FOREIGN PATENT DOCUMENTS

2149943 3/1973 France .

FIG. 5 is a left end elevational view thereof;

FIG. 6 is a right end elevational view thereof;

FIG. 7 is a bottom plan view showing an angle member and
a holder of the implant in separated condition;FIG. 8 is a top plan view of the separated angle member and
holder;FIG. 9 is a left end elevational view of the separated angle
member and holder;FIG. 10 is a right end elevational view of the separated angle
member and holder;FIG. 11 is a left side elevational view of the separated angle
member and holder;FIG. 12 is a right side elevational view of the separated angle
member and holder;FIG. 13 is a top, left perspective view showing the separated
angle member and holder;FIG. 14 is a bottom, front perspective view of the holder;
and,FIG. 15 is a top perspective view of the femoral osseointerface
in assembled condition.**1 Claim, 12 Drawing Sheets**FIG. 1
